FOOD DISPLAY PACKAGE

Jack V. Cline, Hinsdale, Ill., assignor to Tee-Pak, Inc., a corporation of Illinois

Filed Dec. 20, 1967, Ser. No. 9,870

Term of patent 14 years

Int. Cl. D9—04

U.S. Cl. D9—216

The figure shown is an isometric view of a food display package.

The side not shown is the same as the side shown and the bottom is substantially plain and unornamented.

I claim:

The ornamental design for a food display package, substantially as shown and described.
